TRAIN ORDER HOOP HOLDING MEANS

Application filed September 18, 1931. Serial No. 563,514.

My invention relates to means especially adapted for holding the usual train orders intended for the trainmen of a moving train which is not intended to stop at the station 5 where the orders are received by the station man to be delivered to a subsequently passing train.

My invention has for its object the provision of means which will properly hold 10 the orders at proper elevation for the respective members of the train crew who are intended to receive the orders; said means obviating the necessity of the station man manually delivering the orders, as has heretofore been customary, and therefore eliminating 15 the hazards attending such manual delivery.

My invention also involves means whereby 20 the order holding hoops, employed for such purpose, will be positively released at the proper moment when the arm of a member of the train crew has passed into the hoop or loop portion of the order holder, thus ensuring delivery of the orders without the 25 necessity of the train crew member assuming a dangerous position in his effort to grasp the holder.

The invention also involves means which 30 ensures the holders with the orders to remain in proper position relative to the direction of train movement, as well as other objects and advantages which will be readily comprehended from the following detailed description 35 of the accompanying drawings, wherein:

Figure 1 is a side elevation of my improved holder, with intermediate portions broken away.

Figure 2 is a front elevation of the same 40 with similar portions broken away.

Figure 3 is an enlarged front elevation of one of the hoop holder elements, with portions of the supporting uprights.

Figure 4 is a side elevation of one of the 45 elements, showing a section of the handle of an order holding hoop in place; a portion of one of the supporting uprights being in section; and a portion of a corresponding element broken away.

Figure 5 is a sectional view taken sub-

stantially on the line 5—5 of Figure 3 looking downward.

Figure 6 is a sectional view taken substantially on the line 6—6 of Figure 1.

Figure 7 is a perspective view of one of 55 the holding devices with a portion of an order holder in place and portions of the supporting uprights.

The object of my invention is the provision 60 of mechanical means for properly holding the train order holding hoops at a railway station so as to enable the train crew of a passing train or locomotive to easily and safely receive the hoops with the attached orders.

With the present method of delivering orders to a passing train, the orders or other written communications to be delivered are attached to holders, usually of light wood construction, having one end in the form of a hoop or loop for passage of an arm therethrough, while the other end constitutes a handle to be held by the station man or party who is to deliver the orders to the train crew. At present, the station employee, while standing 70 near the track on which the train is to pass, endeavors to hold the hoops at proper elevation and as near to the position of the intended member of the crew on the passing train as possible, so as to enable the train crew member to catch his intended hoop; this usually being done by holding his arm in position so it will pass through the hoop or loop end of the holder. The orders are then removed from the holders and the holders dropped to the ground or on the station platform 75 where it is retrieved by the station employee for further use. This practice, however, involves the hazard of personal injury both to the station employee and to the receiving member of the train crew.

As the station employee is compelled to stand close to the passing train or locomotive, he is in danger 80 of being hit by lumps of coal or other objects which sometimes fall or are inadvertently thrown from the passing trains.

Then, too, the receiving member or members of the train crew are subject to injury because of the possible failure of the station employee to relinquish his hold on the holder 85 at the proper instant, or by losing his balance 90 95 100

as a result of being compelled to lean too far outward in his attempt to catch the holder; or by having his arm or body striking a mail crane or other obstruction which of necessity 5 must be located close to the track.

In the embodiment of the invention, I have illustrated my improved means adapted to deliver orders or other written communications to the crews of trains passing in opposition to the crews of trains passing in opposite 10 site directions on adjacent tracks; it being understood that the various hoop holding elements are similar in construction and operation, so that specific description of one of said elements will suffice.

15 In the particular exemplification, my improved mechanical means involves suitable supporting members which are shown as preferably consisting of a pair of tubular uprights 15, 15, the lower ends whereof are 20 shown embedded in a supporting base, preferably concrete as at 16 in Figure 1. These uprights are arranged in close parallel relation and disposed at a suitable distance from the tracks; the uprights being held in proper 25 spaced relation by suitable tie straps which may be welded, or otherwise secured thereto, as shown at 17.

These tubular uprights or columns are of a predetermined height so as to permit a suitable number of holding elements to be secured thereto at prearranged distances above the track level and at suitable horizontal distances apart in keeping with the positions of the engine crew and the conductor to whom the orders or written communications are to 35 be delivered.

In the particular exemplification, I have chosen to illustrate my invention adapted to hold and deliver orders to trains moving in opposite directions on adjacent tracks, but it will be understood that where the orders are merely intended for trains moving in the same direction and on a single track, the holding elements disposed on one side of the uprights or columns may be omitted. As these holding elements are all similar in construction and operation, a detailed description of one of the elements will suffice.

50 The holding elements, which are indicated at 18, each consist of a body portion or casting 19 provided with the base plate 20 which is intended to extend parallel with the sides of the uprights 15, 15, while the body portion 55 extends laterally therefrom in a horizontal position.

This body portion is provided with a pair of jaw members 21, 21 arranged one above the other and hingedly secured as at 22 to the base portion, so as to permit the jaw members to move vertically toward and away from each other.

These jaw members are normally forced toward each other by means of the springs 23, 60 65 23, which surround opposite ends of the bolt

24, which passes loosely through apertures in both jaws.

The outer ends of the jaws 21, 21 are provided with the arcuate projections 25, more clearly shown in Figure 4 in order to provide a holding or gripping surface for the handle of the order-holder 26. Any suitable gripping surface may be provided for firmly holding the holders in place against accidental shifting, while at the same time permitting easy insertion of the handle 26^a of the holder 26.

Each jaw member is provided with a tapped hole to receive an adjustable screw 27. The screws 27 are intended to retain an ejector element or bar 28 in its retracted position shown in the drawings; the bar 28 being shown slightly enlarged at 29, 29, whereby the screws 27 engage therewith.

The ejector bar extends transversely between the jaws 21, 21, and each end of the bar is provided with a guide rod or pin 30, rigidly secured thereto and disposed through a suitable opening in the casting side portions 19^a and base 20, see Figure 5. The guide rods or pins 30 are each surrounded by a coil spring 31, as shown in dotted lines Figure 5; the springs 31 being under compression and therefore tending to force the ejector bar 28 outwardly toward the free ends of the jaws.

It is apparent, therefore, that the ejector bar 28 is held under pressure against the side of the handle 26^a of the order holder 26, see Figure 4. The outward movement of the ejector elements is limited by the washer and cotter secured to the unattached end of each guide rod 30, as shown at 32 in Figure 5.

The body castings 19 are shown provided with the laterally disposed and parallelly arranged wings or extensions 33, 33, see Figures 3 and 5. These wings 33 are for the purpose of receiving a laterally disposed vane 34 secured to the holder handle 26^a, which prevents the holder rotating between the jaws and hence ensures the hoop portion 26^b being held in the vertical manner illustrated in Figure 2 so as to be in position for passage of a forearm therethrough.

115 After the order or communication has been properly secured to the respective holder 26, the station operator places the holder in position by inserting the handle 26^a edgewise between the jaw members 21, 21, with the hoop end 26^b disposed toward the track. The arcuate portions 25 at the free ends of the jaws 21 permits the handle to be forced into place and causes the jaw members to move apart against the action of springs 23. The insertion of the holder handle forces the ejector bar 28 rearwardly against the action of springs 30.

120 The bar 28 is free to move backwardly because the ends of the screws 27 will be moved out of the path of the bar by the extreme 130

opening of the jaws induced when the holder handle is passing over the arcuate humps or projections 25 on the jaw ends. The screws 27, however, are so adjusted that they will have slight holding contact with ejector bar 28 when the holder handle has been properly positioned between the jaws rearward of the raised arcuate portions 25, see Figure 4.

It is apparent that as soon as a slight pulling action is exerted on the order holder 26, it will ride up on the arcuate raised portions 25 thereby causing the jaws 21, 21 to move farther apart and as a result cause the screws 27 to move out of holding contact with the ejector bar 28. As the bar 28 extends lengthwise of the handle 26^a of the holder, the holder will be forcibly ejected through the action of the springs 31 on the ejector bar. With this construction, the order holder will be instantly released and ejected as soon as the member of the train crew catches or exerts a slight pulling action on the holder; it being understood that the device is arranged with the free ends of the jaws disposed in the direction of movement of the train, so that the pulling effect on the holder is toward the free ends of the jaws.

As the train conductor and each engine man of the train must receive a copy of every order addressed to the train, it is essential that at least two and sometimes three of the order holding devices must be arranged on the supporting uprights.

As the firing decks or gangways of a locomotive are usually in a considerably higher plane above the level of the track than the steps of the coaches or of the caboose, the holding devices 18 must be arranged at different levels as shown in Figures 1 and 2; the levels corresponding to the levels of the positions of the receiving members of the train crew. The holding devices 18 for the crew of a train moving in one direction are disposed laterally from the supporting uprights in the direction of that track, while the devices 18 for the crew of a second train moving on a second track are disposed in the direction of movement of the train on said second track, as shown in Figure 1, where it is assumed that the tracks will extend parallel with the front and rear sides of the device as viewed in said figure.

As the holding devices 18, when in functioning position, will be considerably above the ground and in order to insert the different order holding hoops 26, the holding devices are slidably mounted on the uprights. To accomplish this, I provide a carriage 35 composed of two plates adapted to be slidably disposed on opposite sides of the uprights 15, 15 and united together by the parallel members or plates 36, which may be welded or otherwise suitably secured to the first mentioned plates; the plates 36 extending between the two uprights 15, 15 as shown in Figure 5.

The outer plates or members of the carriage 35 are apertured to receive the bolts 37, whereby the pair of holding devices 18 on opposite sides of the uprights are secured to the carriage 35; the bolts 37 passing between the spaced apart plates 36 as shown in Figure 5.

The intermediate and lower holding devices are similarly mounted on a similar carriage; and these carriages are secured together in proper vertically spaced relation by means of a tie bar or rod 38, thus causing all of the holding devices 18 to move in unison when desired.

The upper carriage 35 has a cable or chain secured to upper ends on both sides of the uprights 15, 15; and these cables or chains 39 extend upwardly to the upper ends of the uprights 15, 15 and respectively pass over the pulleys 40, 40, which are suitably mounted in the uprights; and each chain or cable 39 has its other end secured to a counterweight 41, see Figure 4. The counterweights 41 are of a construction which permits them to freely slide upwardly and downwardly within the respective upright 15; see Figure 4. The pulleys 40 are supported by yokes or other means which are adjustably mounted in order that proper positioning of the pulley may be obtained to insure free action of the carriages 35, the chains or cables and the weights.

The weights 41 are preferably made slightly lighter than the combined weights of carriages, tie bar or rod and the holding devices so as to permit these elements to gradually slide downwardly when the carriage locking means is released.

The locking means, which may be of any suitable construction, is preferably attached to the lower carriage 35 which is shown provided with a lateral extension or ear at 42, see Figure 1, to which a suitable hand operated pawl 43 is pivotally secured. The pawl 43 is normally held in horizontal locking position by a suitable spring as shown at 44, Figure 1; and one of the uprights 15 is provided with a vertical row of properly spaced holes as at 45 (see Figure 2) adapted to receive the inner end of the pawl 43 when the latter is in horizontal position, to which it will be returned by the spring 44 when the operator releases his hold on the pawl. When the pawl end has entered a hole 45, the carriages with the holding devices 18 will be held against downward movement.

When the train is handled by one locomotive, merely the upper and lower holding devices 18 are employed; the intermediate holding device being more particularly employed where two locomotives are used in handling the same train.

In order that the device and the orders may be properly visible at night, I provide a suitable conduit as at 46 provided with current conducting wires leading from a suit-

able current supply and extending to a suitable, preferably shielded lamp 47 secured to the upper end of the conduit 46.

The orders to be delivered are usually folded and placed by the station operator between the staff or handle portion 26^a and the free end of the looped portion 26^b of the hoop 26; these portions being preferably held in closelapping contact by a suitable wire clip as at 48 in Figure 2. In order to prevent ingress of snow, rain and the like, into the uprights 15, 15 and to protect the pulleys, the uprights are preferably provided with a suitable closure member or cap as at 49. 15 The station operator, after having attached the respective copies of the order or orders to the required number of hoops, releases the latching pawl 43, enabling him to pull the carriages with the holding devices 18 downward into easy reach. He then inserts the order holding hoops in the respective holding devices 18 by pressing the hoop handles edgewise between the jaws as previously described so as to have the looped or hoop portion 26^b of the holders disposed 20 or 25 toward the track on which the train is approaching.

It will be understood that with the order holding hoops 26 arranged as shown in Figure 2, the train is presumed to come toward the device as viewed in Figure 2 so that the arms of the receiving members of the train crew will pass through the loops 26^b toward the front as viewed in this figure.

As soon as contact is made with the order holding hoop, it will slide up on the arcuate humps on the jaws, cause the latter to separate, and thereby raise the beveled screws out of contact with the ejector bar, with the result that the entire hoop will be quickly ejected from the holding means.

For the purpose of exemplification of the invention, I have illustrated and described an accepted embodiment arranged to meet certain conditions in railroad practice, but it is apparent that modifications may be made; the invention having been described in terms employed for purposes of description and not as terms of limitation as modifications are possible without departing from the spirit of my invention.

What I claim is:

1. Means of the character described comprising vertically disposed supporting means; order-holder holding means mounted on the supporting means and adapted to release the holders in the direction of train movement; and means whereby the holders are automatically ejected from said holding means.

2. In means of the character described, order-holder holding means comprising jaw members adapted to receive the holder therebetween; a spring controlled ejector; and means operatively associated with the jaw

members whereby the ejector element is held in retracted position.

3. In means of the character described, order-holder holding means comprising jaw members adapted to receive the holder therebetween, and ejector means adapted to automatically eject the holder from the jaws when the latter move toward open position.

4. Means of the character described comprising vertically disposed supporting means; order-holder holding means slidably mounted on the supporting means; means whereby the holding means are held at predetermined positions; and means whereby the holders are ejected from the holding means when pressure on the holders in a prearranged direction is exerted.

5. Means of the character described comprising supporting means; order-holder holding means involving vertically movable jaws adapted to edgewise receive the holders; means for ejecting the holders from the holding means when pressure on the holders in a pre-arranged direction is exerted; and means whereby the holders are held against accidental rotative movement.

6. Means of the character described comprising vertically disposed supporting means; order-holder holding means vertically slidably on the supporting means; means whereby the positions of the holding means may be controlled; and means for automatically ejecting the holders from the holding means when pressure on the holders in a given direction is exerted on the holders.

7. Means of the character described comprising a pair of tubular uprights; carriage members slidably mounted on the uprights and adapted to move in unison; order-holder holding means mounted on the carriage members and adapted to edgewise receive the holders; ejector means associated with the holding means for automatically forcing the holders from the holding means when pressure on the holders is exerted in given directions; means for yieldingly supporting the carriage and holding means; and means whereby the positions of the carriages with the holding means may be determined and the carriages may be locked in place.

8. Means of the character described comprising a pair of tubular uprights provided with pulleys at the upper ends; slidably mounted members disposed on opposite sides of the uprights; counterweights slidable within the uprights and flexibly secured about the pulleys to said members; order-holder holding means secured to said members and involving spring controlled vertically movable jaws adapted to edgewise receive the holders; spring controlled ejectors associated with the holding means; and means whereby the members with the holding means may be positioned on the uprights and locked in place.

9. In means of the character described, order-holder holding means involving vertically movable spring controlled jaws adapted to edgewise receive the holders therebetween; spring controlled ejector bars associated with the holding means for forcibly ejecting the holders when pressure on the holders is exerted in given directions; and means associated with the jaws whereby the ejector bars are held in retracted position when the jaws are in holder clamping positions.
10. In means of the character described, for holding a train order holder, a base member; a pair of jaw members arranged in spaced relation one above the other and secured to the base member so as to permit vertical movement of the jaw members; means adjacent the outer ends of the jaw members for restricting the order holder receiving passage between the jaw members and whereby the latter are caused to move apart when pressure on the holder is applied in a direction lengthwise of the jaw members; means whereby the jaw members are normally forced toward each other; ejector means associated with the jaw members for automatically forcing the holders from between the jaw members when pressure on the holders is exerted toward the outer ends of the jaw members; and means associated with the jaw members for retaining the ejector means in retracted position until the jaw members are caused to move in separating direction.
11. Means for holding the handle of a train order holder comprising a pair of jaw members arranged in spaced relation one above the other and adapted to move vertically, the outer ends of the jaw members having vertical portions disposed toward each other for restricting the order holder receiving passage and to cause the jaw members to separate when pressure on the holder is applied in a given direction; means whereby the jaw members are yieldingly held in closed position; a spring controlled ejector bar mounted between the jaw members and movable lengthwise of the jaw members; and means associated and movable with the jaw members for holding the ejector bar in retracted position until the jaw members move in separating direction.

WILEY L. WHITE.
